GEORGE E. NEUBERTH, OF NEWARK, NEW JERSEY.

HINGE.

1,149,212.

Specification of Letters Patent. Patented Aug. 10, 1915.

Application filed March 27, 1915. Serial No. 17,377.

To all whom it may concern:

Be it known that I, GEORGE E. NEUBERTH, a citizen of the United States, and a resident of Newark, county of Essex, and State 5 of New Jersey, have invented certain new and useful Improvements in Hinges, of which the following is a specification.

This invention relates to a hinge which supports a window, door or other element 10 that is adapted to be held in swinging relation in a frame, and holds such element so that it can be lowered into a groove or on a projection of the sill or at any other point, and which also can be raised when it is to be 15 lowered into place.

The invention is further designed to provide a hinge of this kind in which the operating part is concealed so that it is not adapted to be interfered with by the entrance of dirt, and one in which the part directly attached to the element, such as a door or window sash, is strongly attached thereto 20 by reason of a right-angled portion forming both a butt plate and a front plate, so that all strain of the supporting of the window when it is swung clear of the sill is not borne by screws or similar devices put in the butt 25 plate. In types of hinges that permit the lowering and raising of the supported or hinged element the window when lowered usually sets so that the groove in its bottom is placed over a ridge on the sill, or 30 there is a groove in the sill which receives the window sash or the door. This makes a weather-tight joint, assists in locking the window or door in closed position, but they have been movable when the window is 35

opened, and this is encouraged by misuse of the hinge in that the window or door has been lowered when partly open so as to lock it in place, and the weight of the door or window resting on a rib or the edge of a 40 groove has tended to flatten the structure on which it rests and thus deforms such part so that the door or window is not adapted to fit when it is closed. Furthermore, such lowering of the window or door when open 45 tends to scratch or mutilate the sill, and to overcome this chance of mutilation and damage I have provided a lock in my hinge which locks the structure so that as soon as the window is opened, even to a slight ex-

tent, the lock is placed in operative position 55 and it is not possible to lower the sash or door until it is again swung to its closed position, and the closing of the hinge automatically releases the lock, and by operating the handle of the hinge the window can be 60 lowered into place.

The invention is further designed to provide a hinge having few parts, which are of a form to insure long wear and to make a stiff structure that will not break easily nor 65 rattle, and one in which there is a positive limitation to the swinging of the handle so that the parts can not be unduly strained.

The invention is illustrated in the accompanying drawing, in which I illustrate one 70 embodiment of my invention, but it will be understood that other forms and parts can be employed, and that I am not limited to the particular hinge shown in the illustration.

In said drawing, Figure 1 indicates a front view of the hinge showing part of the frame and part of the door or window sash, in this figure the door being shown raised, so that it is in swinging position. Fig. 2 80 is an edge view of the hinge with one of its leaves removed so as to show the inner face of the other leaf. Fig. 3 is a top view of the hinge shown in Fig. 1. Fig. 4 is a perspective view of one of the members of one 85 of said hinged leaves, and Fig. 5 is a perspective view of part of another member of said hinged leaf, Fig. 5 being adapted to fit against the back of Fig. 4.

In the drawing, 10 illustrates the edge of 90 a door or window frame and 11 is the element that is supported by the hinge, this element being a door, window, sash or other structure that is to be swung, and which is supported by the hinge which consists of 95 hinged leaves, the form shown having leaves that form a butt hinge, that is, the leaves can be swung to substantially a parallel relation. One of the leaves 12 shown in this type of hinge is an ordinary hinge leaf with 100 holes 13^a by means of which it can be attached to the frame 10, the leaf 12 having knuckles 13. The second hinge leaf comprises two members. One of them, a supporting member, consists of a plate 14 having knuckles 15 thereon, which knuckles and the knuckles 13 are spaced so as to surround a pintle 16 with suitable heads 17 which can

be permanently or detachably arranged on the pintle, it being possible, however, to permanently affix these heads, since they need not be removed. The plate 14 has a 5 right-angled part 18 which has an opening 19 therein, this opening being preferably rectangular whereby the right-angled part is provided with upper and lower strips 20 and 21 with an edge strip 22 which preferably 10 has a side extension 23 which fits around the outside of a movable member to be hereinafter described. The movable member 24 has a recessed part with shoulders 25 and 26 on its upper and lower portions which fit above and below the right-angled part 18 of the supporting member 15 and have holes 27 to receive suitable supporting means, such as screws 28, which also pass through a face plate 29, the face plate 20 thus serving, with the part 24 of the supporting member, to inclose the right-angled part 25 of the supporting member.

The movable member 24 is preferably L-shaped having the plate 30 with suitable 25 holes 31 therein through which screws can be passed, this plate 30 forming means for fastening the movable member to the edge of the element to be supported, such as the window or door 11, and the face plate having 30 openings through which the screws 32 are passed, thus forming a plate to go under the face of the element 11 so that right-angled fastening means are provided which prevent undue strain on any of the fastening 35 means and prevent shearing strain on the screws.

To more securely hold the body portion 24 of the movable member and its face plate in their proper relative positions, one of the 40 members, such as the part 24, is provided with grooves 33 and the face plate is provided with projections 34, and in this way the parts are held together and relieve the screws 28 of shearing strain and assist in 45 providing a more rigid structure. A block 35 is placed in the opening 19 and has a side movement in said opening but no appreciable vertical movement therein, and is provided with an eccentric 36 on a shaft 37, the 50 shaft 37 extending into the member 24 and also extending forward through an opening in the face plate and having a projecting end 38. The projecting end is of any suitable 55 form to permit its being turned, the preferred form being rectangular as shown, that is it has a side flattened, and a handle 39 has a boss 40 which is recessed and fits the projecting part 38 and a pin 41 passing through an opening in the boss of the handle and also through the opening 42 in the projecting part 38 of the shaft 37. It will 60 thus be evident that when the handle is placed in the position shown in Figs. 1 and 2 the eccentric is so held that its center is 65 below the shaft of the handle and the eccen-

tric thus raises the shaft 37 and consequently the movable member comprising the part 24 and the face plate 29, and the window is raised to a position where it can be swung from any recessed part or from fitting over any rib or any of the usual forms of receiving elements, such as doors and windows, and the element 11 is free to be swung to any position. This raised position is maintained by reason of the block 35 resting against the bottom bar or rail 21 of the right-angled part 18 of the supporting member and when the window is to be lowered the handle is swung downward and the shaft 37 is placed at a low point on the eccentric and the movable member is thus moved to a lower position, this being possible on account of the cut-away part 43 in the plate 30 and the narrowed portion 44 of the plate 14, the opening at the ends being sufficient to permit the vertical movement of one on the other. The swinging movement is permissible on account of the opening 19 being wider than the block 35, and side movement sufficient to permit the eccentric 36 to swing from one vertical position to another is possible. The extension 23 on the end of the right-angled part 18 fits around the back edge of the plate 24 and also serves to hold the parts in better alignment and to prevent the entrance of dirt from the wood, and splinters and the like in the case of a wooden door, from interfering with the easy operation of the hinge.

To prevent the lowering of the door or window 11 when it is in any other place but in its closed position, I provide a lock which can be of different forms, the one illustrated, however, consisting of a latch 45 slidably arranged in the back of the member 24 and normally pushed forward by a spring 46 abutting at one end on the wall 47 and at its other end on the latch 45. The latch 45 is operated by means extending to the exterior of the casing, one form being a finger 48 which projects from the edge of the movable member when the spring is in place, and the finger is pressed in against the influence of the spring when the leaves are swung to their closed positions, that is when they are swung together, and it is then engaged as shown in Figs. 1 and 2, and this pushes the latch back until it is opposite the recess 49 in the top of the right-angled part 18 of the supporting member. This recess 110 permits the latch to enter it when the movable member is moved downward, and the latch resting on the bottom edge of the shoulder 50, it thus permits the movable member to go with it and the element 11 can 115 thus be lowered into place. When, however, the window is raised and is then opened to swing the hinge leaves apart, the spring 46 presses the latch forward and the latch has 120 its forward end in register with the recess 130

49 and is interposed between the top edge 51 of the part 20 of the right-angled member 18 of the supporting member and the shoulder 50 of the movable member, and this 5 locks the parts against sliding movement and consequently locks the handle against any swinging movement and the window cannot be lowered to the damage of any of the fittings, and the window is thus supported 10 entirely on its hinges and cannot be let down. The forward movement of the latch is limited preferably by means of a stop 52, as will be evident. The movement of the handle is limited by the engagement of the 15 block 35 with the outer strip 23 of the right-angled part 18 of the supporting member.

The particular means described and illustrated are thought to be the preferred forms, but it will be understood that I may use 20 other forms and differently dispose the parts without departing from the scope of the invention.

This hinge has no extreme lengths beyond the lengths of the knuckles and the pintle, is light compared with the duties 25 it performs, is compact, the parts are so disposed and proportioned that the hinge is not easily broken, and its simplicity assures its operation.

30 Having thus described my invention, I claim:

1. A hinge comprising leaves in swinging relation, means on one of said leaves for raising and lowering a part thereof, and a locking means within the hinge for preventing the lowering of said part when the leaves are separated.

2. A hinge comprising leaves in swinging relation, a vertically movable part on one of 40 said leaves, means for raising and lowering said part, and a locking means released by the coöperation of said leaves, the locking means preventing the lowering of said part when the leaves are swung apart.

45 3. A hinge comprising leaves in swinging relation, one leaf comprising a supporting member and a vertically movable member, means for attaching the movable member to an element, a manually operated device on the supporting member for operating the movable member, a yieldingly pressed locking means for holding the movable member against movement, and a finger on said locking means and disposed so that it is operated 50 when the leaves are swung together so as to release the locking means.

60 4. A hinge comprising leaves in swinging relation and held against relative longitudinal movement, one of said leaves comprising a supporting member and a movable member, means for sliding the movable member vertically on the supporting member, a latch to engage the members to lock them against relative movement, a spring to normally force the latch to its locking position, and a 65

finger on the latch and in the path of swinging movement of the opposite leaf, whereby engagement of the finger with said leaf releases the latch.

5. A hinge comprising leaves in swinging relation, one of said leaves consisting of a supporting member having a right-angled part, an L-shaped movable member carried by the supporting member, the L-shaped movable member having means for attaching 70 it to the edge and the face of an element supported thereby, the movable member embracing the right-angled projection of the supporting member, means in the embraced part of said supporting member for causing 75 relative movement between the supporting member and the movable member, said means having a projection extending through said movable member, a handle on said projection, a latch for locking the movable member and the supporting member against relative movement, and a finger on said latch adapted to be engaged by the other of said leaves to release the latch when the leaves are 80 85 90

6. A hinge comprising leaves hinged together, one of said leaves comprising a supporting member and a movable member, the supporting member having a right-angled part with an opening therein, the movable member consisting of a back plate and a front plate to embrace the right-angled part of the supporting member, a block in the opening of the right-angled part of the supporting member, a shaft passing through the front plate and the back plate, an eccentric on the shaft and fitting in the block, and a handle on said shaft for operating it.

7. A hinge comprising leaves hinged together, one of said leaves comprising a supporting member and a movable member, the supporting member having a right-angled part with an opening therein, the movable member consisting of a back plate and a front plate to embrace the right-angled part 105 of the supporting member, a block in the opening of the right-angled part of the supporting member, a shaft passing through the front plate and the back plate, an eccentric on the shaft and mounted in the block, a handle on said shaft for operating it, a latch 110

slidably arranged in the back plate, a spring to force the latch to its locking position, the latch when in locking position engaging the top of the right-angled part of the supporting member, and a finger on said latch and adapted to engage the opposite leaf to slide the latch to its releasing position when the leaves are swung together, the right-angled portion of the supporting member being recessed to receive said latch when in its releasing position.

8. A hinge comprising leaves in swinging relation, one of said leaves comprising parts that are vertically movable in relation to 115 120 125 130

each other, a latch normally lying in a position to lock said relatively movable parts against such movement, and a projection on said latch to move the latch to an inoperative position, the projection being so disposed as to be operated when the leaves are swung together.

Copies of this patent may be obtained for five cents each, by addressing the "Commissioner of Patents, Washington, D. C."

In testimony that I claim the foregoing, I hereto set my hand, this 26th day of March, 1915.

GEORGE E. NEUBERTH.
